UNITED STATES PATENT OFFICE

CLOISE H. BALDWIN, OF FORT WORTH, TEXAS

MACHINE FOR FORMING COAT HANGERS

Application filed March 14, 1930. Serial No. 435,866.

This invention relates to a machine for forming coat hangers and has for its primary object to provide, in a manner as hereinafter set forth, a machine for the above mentioned purpose by means of which a length of wire may have portions thereof bent in proper sequence and in proper relation to the remaining portions thereof to produce a finished coat hanger of the wire type, the latter being ejected from the machine immediately following the completion of the hanger.

A further object of the invention is to provide a machine of the character aforesaid, which may be supplied with a plurality of wires of proper length to be successively operated upon by the machine to produce a plurality of coat hangers of the wire type suspended from a pair of delivery arms, the operation of the machine being entirely automatic from the time that the plurality of wires are supplied thereto.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:

Figure 1 is a front elevation of a machine in accordance with this invention with the feeding mechanism removed therefrom.

Figure 2 is a fragmentary side elevation showing the feeding mechanism.

Figure 3 is a fragmentary front elevation of the feeding mechanism.

Figure 4 is a fragmentary front elevation of the feeding mechanism.

Figure 5 is a detailed view of the means for operating the gripping mechanism.

Figure 6 is a detailed view of the means for operating the bending mechanism.

Figure 7 is a detailed view of the bending

mechanism as viewed from the right of Figure 6.

Figure 8 is a detailed view of the means for operating the folding mechanism.

Figure 10 is a detailed view of the clamping mechanism and means for operating the same.

Figure 11 is a detailed view showing the means for operating the twisting mechanism.

Figure 12 is a top plan of the twister element.

Figure 13 is a sectional detail of the twister mechanism.

Figure 14 is a detailed view of the hook forming mechanism and operating means therefor.

Figure 15 is a detailed view showing the hook forming and ejector mechanisms.

Figure 16 is a detailed view of one of the cam shafts with the cams in place thereon.

Figure 17 is a fragmentary elevation showing the driving means for the cam shaft for operating the several mechanisms.

Figure 18 is a diagrammatic view showing the gripping and bending mechanisms in operative position with respect to a length of wire being formed into a coat hanger.

Figure 19 is a similar view showing the folding and clamping mechanisms in operative position with respect to the length of wire.

Figure 20 is a similar view showing the twisting mechanism in operative position with respect to the length of wire.

Figure 21 is a similar view showing the hook forming mechanism in operative position with respect to the length of wire.

A coat hanger forming machine in accordance with this invention consists of a feeding mechanism for successively moving a plurality of wires into position to be operated upon, gripping mechanism for receiving the wires from the feeding mechanism, bending mechanism for bending end portions of the wires obliquely to adjacent portions thereof, folding mechanism for forming the body por-

65

70

75

- tion of the hanger and for bringing the obliquely bent end portions of the wire into juxtaposition, clamping mechanism for securing the obliquely bent end portions of the wires in juxtaposition, twisting mechanism for securing the obliquely bent end portions together, hook forming mechanism for bending one of the secured end portions into the shape of a hook to complete the hanger, 5 ejecting mechanism for ejecting the completed hanger from the machine, and driving means for operating the several mechanisms in proper sequence.

The several mechanisms are supported by 15 means of a base 1 having a skeleton frame 2 extending upwardly therefrom, and are operated by means of a pair of cam shafts 3 and 4 respectively. The cam shafts 3 and 4 extend from front to rear with respect to the 20 machine, the cam shaft 3 being located centrally of the sides of the frame 2, and the cam shaft 4 being located on the left side of the frame 2 when viewed from the front as in Figure 1. The cam shafts 3 and 4 are 25 provided at their rearward ends with bevelled gears 5 and 6 respectively which are operated at equal speed in opposite directions by means of a pair of pinions 7 and 8 fixedly mounted on a common shaft 9. Fixedly mounted on the shaft 9 is a gear 10 which is in mesh with 30 a pinion 11 fixedly mounted on a power shaft 12 which may be operated by any suitable means, not shown. Projecting upwardly from the frame 2 are a pair of pedestals 13 35 which rigidly support a rod 14 extending therebetween.

Feeding mechanism

This mechanism consists of a pair of spaced 40 angular supporting members 15 adapted to have a plurality of wires 16 supported thereon and disposed at a downward and rearward inclination. The supporting members 15 are supported in front of the machine by means 45 of a frame 17 mounted on the upper ends of a pair of rigid arms 18, the lower ends of which are connected with the base 1. The supports 15 are further supported by means 50 of a pair of braces 19, the respective ends of which are rigidly connected with the frame 17 and rod 14 extending between the pedestals 13. Pivotaly connected to the frame 17 are the forward ends of a pair of links 20, the rearward ends of which are pivotally connected to a pair of carrier members 21 intermediate the ends of the latter. The upper 55 ends of the carrier members 21 are pivotally connected to the forward ends of a pair of rocker arms 22 mounted on the rod 14 whereby longitudinal movement is imparted to the members 21 upon rocking movement of the rocker arms 22. Spaced from the lower ends thereof the members 21 are provided in their forward faces with notches 23 which are 60 adapted to receive the rearmost of the wires 65

16 therein. Upon a movement of the members 21 in a downward direction, the rearmost of the wires 16 is carried thereby along a pair of guide members 24 projecting from the frame 17 and is deposited on a plurality 70 of resilient fingers 25 carried by a rod 26 mounted on the upper ends of a pair of swinging arms 27, the lower ends of which are connected with a cross member 28 which is rotatably mounted on a pair of brackets 29 75 projecting forwardly from the base 1. Centrally thereof the cross member 28 is provided with an upstanding arm 30 which is provided at its upper end with a roller 31 in contacting relation with a cam 32 provided on the cam shaft 3 at the forward end of the latter. The roller 31 is maintained in contact with the cam 32 by means of a pair of springs 33 which extend rearwardly from the rod 26 and are connected with the frame 2. In Figure 2 the carrier members 21 are shown at the extreme upper ends of their paths of longitudinal movement, and the swinging arms 27 are shown at the rearward extremities of their paths of swinging movement with the fingers 80 25 in position to deliver one of the wires 16 to the gripping mechanism of the machine which will be hereinafter described. When the swinging arms 27 move forwardly from the position shown in Figure 2, the wire 16 carried by the fingers 25 will be freed therefrom owing to the resiliency of the fingers, and the fingers 25 will be provided with a similar wire 16 by the downward movement of the carrier members 21. Projecting upwardly from the rod 26 are a pair of guides 34 for abutment with the ends of a wire 16 85 when the latter is being delivered to the fingers 25 by the carrier members 21.

Gripping mechanism

This mechanism consists of a pair of spaced supporting members 35 rigidly supported from the frame 2 and disposed in the vertical plane of the wire 16 which has been carried 90 rearwardly by the resilient fingers 25. The supporting members 35 are formed with inwardly and downwardly inclined upper faces, and adapted to coact with such upper faces is an arcuate clamping member 36, the lower face of which has portions arranged in opposing relation and conforming in contour with the upper faces of the supporting members 35. The ends of the clamping member 36 merge into a pair of vertical rods 37, the upper ends of which are pivotally connected with the forward ends of the rocker arms 22. The clamping member 36 is normally maintained in spaced relation to the supporting members 35 by means of a pair of compression springs 38 which bear against the lower faces of a pair of shoulders 39 formed on the rods 37. Just prior to the forward movement of the resilient fingers 25, the clamping element 36 is moved downwardly 95 100 105 110 115 120 125 130

to secure the wire 16 supported by the fingers 25 against the supporting members 35 whereby the wire is removed from the fingers when the latter move forwardly. The downward movement of the clamping member 36 is accomplished by means of a cam 40 mounted on the cam shaft 3 and disposed below a roller 41 carried by a cross head 42 at the lower end of a pair of vertically disposed rods 43. Connected to and extending transversely of the rods 43 at the upper ends of the latter is a rod 44, to the outer ends of which the rearward ends of the rocker arms 22 are pivotally connected. When a high portion of the cam 40 contacts with the roller 41, the rocker arms 22 are rocked on the rod 14 in a manner to swing the forward ends of the rocker arms 22 in a downward arc.

Bending mechanism

This mechanism consists of a pair of swinging forms 45 located outwardly with respect to the supporting members 35 and formed with angular upper faces 46. The forms 45 are mounted on the lower ends of a pair of curved brackets 47, the upper ends of which are pivotally mounted on a rod 48 extending transversely of the machine. The forms 45 are normally maintained rearwardly of the plane of the supporting members 35 by means of a pair of springs 49 which extend rearwardly from the forms 45 and which are connected at their rearward ends to the frame of the machine. Coacting with the angular upper faces of the forms 45 are a pair of substantially triangular heads 50 which are carried on the outer ends of a pair of arms 51 extending transversely of the machine and merging at their inner ends into a pair of shafts 52 extending from front to rear of the machine and rotatably mounted in a pair of bearings 53 mounted on the rod 48. At the rearward ends thereof the shafts 52 terminate in a pair of outwardly disposed cranks 54 which are pivotally connected adjacent their outer ends with a pair of downwardly and inwardly extending rods 55. The lower ends of the rods 55 are pivotally connected with a cross head 56 which is provided with a roller 57 located beneath a cam 58 mounted on the cam shaft 3. The cross head 56 is slidably mounted on a pair of vertically disposed guides 59 suitably connected with the frame of the machine. The cross head 56 is provided with a pair of brackets 60 to which are secured the lower ends of a pair of tension springs 61, the upper ends of which are suitably connected with the frame of the machine. The springs 61 maintain the roller 57 in engagement with the cam 58 and normally maintain the heads 50 on the arms 51 in spaced relation to the forms 45 as shown in Figure 1. When the high portion of the cam 58 is brought into engagement with the roller 57, the shafts 52 are rotated whereby the arms

51 are swung downwardly to bring the heads 50 into operative position with respect to the forms 45. Upon the swinging of the arms 51 downwardly, the forms 45 are swung forwardly by means of rollers 62 mounted on the outer ends of the cranks 54. The downward movement of the cranks 54 causes the rollers 62 to ride along the inclined rearward faces 63 of the brackets 47 whereby the latter are swung forwardly about the rod 48 to bring the forms 45 beneath the wire 16 supported in the gripping mechanism. At the same time the heads 50 are forced against the wire and the latter is forced to assume the contour of the angular faces 46 of the forms 45 whereby the end portions of the wire are bent obliquely to adjacent portions thereof. The wire is supported by the gripping mechanism in a manner to project one end thereof beyond one of the forms 45 a greater distance than the opposite end of the wire is projected beyond the opposite form 45. In this manner the wire is provided with a relatively long obliquely disposed portion 64, and a relatively short obliquely disposed end portion 65.

Folding mechanism

This mechanism consists of a pair of angular arms 66 which are adapted to swing in downward arcs to bring the outer ends of the arms into engagement with the wire 16 outwardly of the supporting members 35. Upon the downward movement of the arms 66 the wire 16 is bent in a manner to form the body portion of the coat hanger, and at the extreme downward movement of the arms, the obliquely disposed end portions 64 and 65 of the wire are disposed in parallel relation with the outer end of the portion 64 projecting beyond the outer end of the portion 65. The arms 66 are fixedly mounted on shafts 67 which extend from front to rear of the machine and are journaled in bearings 68 carried by the transversely extending rod 48. Fixedly mounted on the shafts 67 are a pair of segmental bevel gears 68 which are in mesh with a pair of bevelled gears 69 fixedly mounted on a shaft 70 extending transversely of the machine. At one end thereof the shaft 70 is provided with a crank 71 having a section 72 of a connecting rod pivotally connected therewith. Connected with the section 72 by means of a turn buckle 73 is another section 74 of the connecting rod, such other section being pivotally connected to a lever 75 having one end rotatably mounted on a stationary shaft 76 carried by the base 1 and disposed outwardly with respect to the cam shaft 4. Fixedly mounted on the cam shaft 4 is a cam 77 for operating the lever 75. The arms 66 are normally maintained in their upper position by means of a tension spring 78, the ends respectively of which are connected with the lever 75 and a bracket 79

projecting from the frame 2. When a high portion of the cam 77 contacts with the lever 75 the shaft 70 is rotated by the crank 71, and the rotation of the shaft 70 is transmitted through the gears 69 and 68 and shafts 67 to the arms 66 to swing the latter in downward ares to fold the body portion of the coat hanger.

Clamping mechanism

10 This mechanism includes a pair of spaced vertically slidable bars 80, the upper ends of which are connected by means of a cross member 81 with a rod 82 which is secured at its upper end to the forward end of an angular rocker arm 83 rockably mounted on the rod 14 carried by the pedestals 13. The bars 80 are normally maintained in their upper positions by means of tension springs 84 which are secured to a cross member 85 at the rear of the machine and which exert a downward force on the rearward end of the rocker arm 83. Pivottally connected to each of the bars 80 is a pair of toggle levers 86 and 87 which are pivottally connected respectively to a collar 88 slidably mounted on a rod 89 and to a collar 90 fixedly mounted on the rod 89. The rods 89 are slidably mounted in a bearing 91 which is pivottally mounted on the frame 2 to provide for a tilting movement of the rods 89. Fixedly mounted on the forward ends of the rods 89 is the forward jaw member 92 of a vice for coaction with the rearward jaw member 93 of the vice, the rearward jaw member being secured to the collars 88. Downward movement of the slidable bars 80 is effected by means of a pair of downwardly extending rods 94 connected therewith and with a cross head 95 which is provided with a roller 96. Engaging the roller 96 is a cam 97 fixedly mounted on the cam shaft 3.

25 The cam 97 is formed with a peripheral portion 98 disposed a greater distance from the shaft 3 than a peripheral portion 99 of the cam, while the portion 98 is disposed a lesser distance from the shaft 3 than the major peripheral portion 100 of the cam. When the portion 99 is in contact with the roller 96, the slidable bars 80 are in their upper positions and the vice jaws 92 and 93 are opened. When the portion 98 of the cam is brought into contact with the roller 96, the bars 80 are moved downwardly to position the collars 88 50 upon a cross member 101 extending transversely of the machine. When the portion 100 of the cam is brought into contact with the roller 96, the bars 80 are again moved downwardly whereby the jaws 92 and 93 are moved toward each other through the action of the toggle levers 86 and 97. The jaw 92 is normally maintained in spaced relation to the jaw 93 by means of compression springs 102 encircling the rods 89 at the rearward 65 ends of the latter. During the downward

movement of the bars 80, the same remain at rest in the position shown in Figure 9 a sufficient length of time for the wire from which the coat hanger is being formed to be inserted between the jaws by the action of the arms 66 of the folding mechanism. Upon the continued downward movement of the bars 80 the jaws 92 and 93 are moved together as previously described to clamp the wire therebetween.

70
75

Twisting mechanism

This mechanism consists of a frame 103 slidably mounted by means of a pair of spaced ears 104 on a pair of vertically disposed guide rods 105 secured to the frame of the machine. Between the guide rods 105, the frame 103 is formed with an enlarged portion 106 having a horizontally disposed opening 107. Extending through and supported by the enlarged portion 106 is a shaft 108 upon which is fixedly mounted a pinion 109 which is disposed within the opening 107. Formed on the upper end of the shaft 108 is a cylindrical member 110 which is formed with a longitudinally extending opening 111 which is oblong in cross section, and the upper end of which is flared as indicated at 112. Upon movement of the member 110 in an upward direction, the oblique end portions 64 and 65 of the wire from which the hanger is being formed are projected into the opening 111. Sliding movement of the frame 103 is effected by means of a link 113 having one end pivottally connected with the frame and having its other end pivottally connected with a lever 114 which is pivottally mounted intermediate its ends on a bracket 115 projecting from the frame 2. The outer end of the lever 114 is provided with a roller 116 for engagement with a cam 117 fixedly mounted on the cam shaft 4. The roller 116 is maintained in engagement with the cam 117 by means of a rigid, angular bracket 118 to which one end of a rod 119 is pivottally connected. The opposite end of the rod 119 is secured by means of a strap 120 to the lower end of a vertically disposed leaf spring 121. When a low portion of the cam 117 comes in contact with the roller 116 the outer end of the lever 114 is depressed by the action of the spring 121, whereby the frame 103 is moved upwardly on the guide rod 105.

115
120
125
130

Meshing with the pinion 109 is a rack bar 122 which is mounted for sliding horizontal movement in a pair of guides 123 carried by the frame 103. One end of the rack bar 122 is connected by means of a link 124 with the upper end of a lever 125, the lower end of which is rotatably mounted on the stationary shaft 76 heretofore described. Carried by the lever 125 is a roller 126 which is maintained in engagement with a cam 127 on the cam shaft 4 by means of a tension spring 128, the respective ends of which are connected

with the lever 125 and with a strap 129 secured to the frame of the machine. When a high portion of the cam 127 is brought into contact with the roller 126, the rack bar 122 is moved longitudinally whereby the cylindrical member 110 is rotated to twist the obliquely bent portions 64 and 65 of the wire for securing them together. The twist in the end portions 64 and 65 formed by the rotation of the member 110 is clearly shown in Figure 21 and is indicated by the reference character 130.

Hook forming mechanism

This mechanism consists of a pair of shafts 131 and 132 extending from front to rear of the machine, said shafts being rotatably and slidably mounted adjacent their rearward ends in a bearing member 133 fixedly secured to the frame of the machine at the rear side thereof. The shafts 131 and 132 are rotatably mounted adjacent their forward ends in a slideable bearing 134 which is slidably mounted on a pair of guide rods, one of which is indicated at 135. The bearing 134 seats on a plate 136 secured to the frame of the machine and is provided in its lower face with a notch 137 for the reception therein of a rib 138 formed on the upper face of the plate 136 and extending from front to rear of the machine. Disposed on the shafts 131 and 132 respectively are a pair of fixedly mounted collars 139 and 140 which bear against the rear face of the bearing 134 to provide for unitary movement of the shafts 131 and 132 and the bearing 134 rearwardly of the machine when a rearward force is exerted on the bearing.

Fixedly mounted on the forward end of the shaft 131 is a crank 141 which is provided with a forwardly projecting head 142. Fixedly mounted on the forward end of the shaft 132 is a curved arm 143 which is provided at its outer end with a forwardly projecting head 144. Fixedly mounted on the rearward end of the shaft 132 is an upwardly extending, curved bar 145, the upper end of which is connected to one end of a tension spring 146, the opposite end of which is secured to a bracket 147 supported from the frame of the machine. Extending in the same direction as the spring 146 is a relatively heavy chain 148, the respective ends of which are connected with the bar 145 and a cross member 149 extending transversely of the machine. Extending in the opposite direction to the spring 146 and having one end pivotally connected with the bar 145 is a link 150, the opposite end of which is pivotally connected with one end of an equalizer 151. Secured to the opposite end of the equalizer 151 is a flexible element 152, such as a chain, which operates in one of the grooves 153 of a double shive wheel 154 fixedly mounted on the rearward end of the shaft

131. Operating in the other groove 153 of the double shive wheel is a similar flexible element 155, the outer end of which is connected with a tension spring 156 which is secured to a bracket 157 pivotally supported from the frame of the machine. The inner ends of the flexible elements 152 and 155 are connected with the double shive wheel 154 by means of a pin 158 which is common to both flexible elements.

The equalizer 151 is pivotally connected intermediate its ends to a lever 159 which is rotatably mounted at its lower end on the stationary shaft 76 heretofore mentioned. Carried by the lever 159 is a roller 160 for engagement with a cam 161 fixedly mounted on the cam shaft 4. The roller 160 is maintained in contact with the cam 161 by the tension of the springs 146 156, and when a high portion of the cam contacts with the roller 160 the upper end of the lever 159 is swung in an outward direction. Owing to the equalizer 151 the outward movement of the upper end of the lever 159 is imparted first to the shaft 132 through the link 150 and bar 145. In the normal position of the bar 145 the chain 148 is slack and when the bar 145 is moved a sufficient distance to remove such slack, any further movement of the bar 145 is prevented. When the bar 145 reaches the limit of its movement, the continued movement of the lever 159 causes a rotation of the shaft 131 owing to the shive wheel 154 fixedly mounted thereon, and to the flexible element 152 connecting the shive wheel with the equalizer. While the bar 145 moves only a very short distance, the movement of the lever 159 is sufficient to rotate the shaft 131 through an arc of substantially 190°. Upon the movement of the shaft 132, the curved arm 143 is swung in an arc whereby the head 144 thereof is forced against the projecting end portion 64 of the wire being operated upon to slightly bend such end portion around a pin 162 projecting from the forward face of the bearing 134. Upon the rotation of the shaft 131, the crank 141 is swung in an arc to bring the head 142 thereon into contact with the end portion 65 of the wire beneath the point of contact between the wire and the head 144. The movement of the crank 141 continues until the end portion 65 of the wire is bent into the shape of a hook as indicated at 163.

Ejecting mechanism

This mechanism consists of a pair of slidably mounted rods 164 extending from front to rear of the machine and formed at their forward ends with curved contact members 165 for engagement with the rear side of the completed coat hanger adjacent the supporting members 35. The rods 164 are pivotally connected at their rearward ends to one end of a pivotally mounted bell crank 166, the

opposite end of which is pivotally connected to a link 167 rigidly connected by means of a bracket 168 to one end of a bell crank 169. The opposite end of the bell crank 169 is provided with a roller 170 which is maintained in engagement with a cam 171 on the cam shaft 3 by means of a tension spring 172, the respective ends of which are connected with the bell crank 169 and the frame 2 of the machine. When a high portion of the cam 171 contacts with the roller 170 the rods 164 are moved forwardly whereby the coat hanger is removed from the supports 35 by means of the contact members 165. Upon the removal of the coat hanger from the supports 35, the hanger is deposited on a pair of downwardly inclined delivery arms 173 which are upwardly curved at their outer ends. The delivery arms 173 are secured to the supporting members 35. Simultaneously with the forward movement of the rods 164 to remove the completed coat hanger from the supporting members 35, the hook forming heads 142 and 144 are drawn rearwardly out of the path of the coat hanger by means of a link 174, the respective ends of which are pivotally connected to the upper end of the bell crank 169 and to a bracket 175 secured to the slidable bearing 134. Upon the actuation of the bell crank 169, the bearing 134 is moved rearwardly, and owing to the contact between the rear face of the bearing 134 and the collars 139 and 140, the shafts 131 and 132 are moved bodily in a rearward direction with the bearing 134. In the operation of the machine as a whole, a plurality of wires 16 of the proper length are deposited by an operator on the support 15 and the cam shafts 3 and 4 are rotated by means of the power shaft 12 and the gearing mechanism connecting the power shaft with the cam shafts. By means of the cam 40 on the cam shaft 3, the rocker arms 22 are rocked on the rod 14 to impart longitudinal movement to the carriers 21 by means of which the rearmost of the wires 16 is removed from the supports 15 and delivered to the flexible fingers 25 carried by the rods 26 supported on the upper ends of the swinging arms 27. The swinging arms 27 are then swung rearwardly by means of the cam 32 whereby the wire which has been deposited on the fingers 25 is moved rearwardly into a position on the supporting members 35. Upon the rocking movement of the rocker arms 22, the clamping member 36 is moved downwardly to press the wire 16 firmly against the supporting members 35 whereby the wire 16 is secured against movement. Upon the securing of the wire 16 between the clamping members 36 and supporting members 35, the swinging arms 27 are returned to their original position whereby the flexible fingers 25 are drawn away from the wire 16 secured by the gripping mechanism. Upon securing of the wire 16 by the grip-

ping mechanism, the arms 51 are swung in downward arcs by the operation of the cam 58 on the shaft 3 whereby the heads 50 on the arms 51 force the wire into engagement with the angular upper faces 46 of the forming blocks 45 which are then brought into position beneath the wire by means of the rollers 62 carried by the cranks 54 on the shafts 52. The coaction between the heads 50 and forming members 45 bends the wire to form the obliquely extending outer end portions 64 and 65. As soon as the portions 64 and 65 have been formed on the wire, the arms 51 and forming members 45 return to their original positions, and the folding arms 66 are swung in downward arcs by the operation of the cam 77 on the cam shaft 4. The downward movement of the folding arms 66 bends the wire 16 into the proper position to form the body portion of the coat hanger, in which position the end portions 64 and 65 are extended in parallel contacting relation, with the outer end of the portion 64 projecting beyond the outer end of the portion 65. The formations of the wire after the operation of the arms 51 and 66 respectively are illustrated in Figures 18 and 19.

Simultaneously with the operation of the folding arms 66, the vice jaws 92 and 93 are moved downwardly by the operation of the cam 97 on the cam shaft 3 into position to receive the folded end portions of the wire therebetween. Upon the reception of the wire between the jaws 92 and 93, the latter are moved toward each other into clamping position by the continued action of the cam 97.

Upon the securing of the wire between the jaws 92 and 93, the twister 110 is moved upwardly by the action of the cam 117 on the cam shaft 4 into a position to receive the end portions 64 and 65 of the wire within the opening 111 formed in the twister. At this time the twister is rotated by the action of the rack bar 122 which is operatively connected with the cam 127 on the cam shaft 4 whereby the portions 64 and 65 of the wire are wrapped around each other as indicated at 130. At the completion of the rotating movement of the twister 110, the roller 126 is in contact with a projection 176 on the cam 127, and when the roller 126 clears the projection 176, the twister is backed off slightly and is lowered to its original position by the operation of the cam 117.

After the completion of the twist 130, the shafts 132 and 131 are successively rotated by the operation of the cam 161 on the cam shaft 4 whereby the heads 142 and 144 on the crank 141 and arm 143 respectively are moved relatively to form the hook 163. The heads 142 and 144 are then drawn rearwardly simultaneously with the forward movement of the ejector rods 164 by the operation of the cam 171 mounted on the cam shaft

3. Upon the deposit of the completed hanger on the delivery arms 173 the succeeding wire to be operated upon is delivered to the gripping mechanism in the manner heretofore described.

5 It is thought that the many advantages of a coat hanger forming machine in accordance with this invention will be readily apparent, and although the preferred embodiment 10 of the invention is as illustrated and described, it is to be understood that changes in the size, shape and arrangement of parts may be resorted to, so long as such changes fall within the scope of the invention as defined in the appended claims.

15 What I claim is:

1. In a coat hanger forming machine, a feeding mechanism comprising, a supporting structure for a plurality of wires, an angularly disposed carrier slidable with respect to the supporting structure for successively removing the wires therefrom, and a cam operated, swinging carrier for receiving the wires from said angularly disposed carrier. 25 2. In a cast hanger forming machine, a gripping mechanism comprising, a pair of stationary supporting members for supporting a length of wire at spaced points intermediate the ends thereof, said supporting members having their upper faces disposed at downward and inward inclinations, and a vertically movable clamp element coacting with said supporting members to grip the wire at said spaced points, said clamp element having an arcuate lower face with portions thereof opposed to and conforming in contour with the inclined upper faces of the supporting members. 30 35

3. In a coat hanger forming machine, a bending mechanism comprising, a pair of swinging forms having angular upper faces for disposition beneath end portions of a length of wire, a pair of swinging arms having angular faced heads for coaction with the upper faces of said swinging forms to bend end portions of the wire obliquely to adjacent portions thereof, means normally maintaining the swinging forms out of the path of travel of said arms, and means for simultaneously swinging the arms and moving the swinging forms into position for engagement therewith. 45 50

4. In a coat hanger forming machine, a clamping mechanism comprising, a slideable rod, a jaw member fixedly mounted thereon, a jaw member slideably mounted thereon, a bar slideable perpendicularly to the rod, and a pair of toggle levers pivotally connected to the slideable bar and respectively pivotally connected with the slideable rod and slideably mounted jaw. 55 60

5. In a coat hanger forming machine, a hook forming mechanism comprising, a pair of rotatable shafts, a crank on one of said shafts and formed with a head, a curved arm

on the other of said shafts and formed with a head, and means for successively rotating said shafts to move said heads into overlapping positions with respect to each other.

6. In a coat hanger forming machine, a hook forming and ejecting mechanism comprising, a pair of rotatable and slideable shafts, a crank on one of said shafts and formed with a head, a curved arm on the other of said shafts and formed with a head, means for successively rotating said shafts to move said heads into overlapping positions with respect to each other, an ejector rod extending in parallel relation to said shafts, and means for simultaneously imparting longitudinal movement to said rod and shafts in opposite directions. 70 75 80

7. In a coat hanger forming machine, means for folding and bending a length of wire to form the body portion of a coat hanger with the end portions of the wire arranged in contacting, parallel relation and with one of said end portions projecting beyond the other, means for securing said end portions together, hook forming members engaging the end portion projecting beyond the other to form a hook, means for slideably mounting said hook forming members, a slideably mounted ejector member, and means connected with the ejector member and the mounting means for the hook forming members to move the ejector and hook forming members in opposite directions simultaneously after the forming of the hook. 85 90 95

8. In a coat hanger forming machine, a hook forming mechanism comprising, a pair of rotatable shafts, hook forming members fixedly connected with the shafts, a swinging lever, a link pivotally connected intermediate its ends to the lever, means connecting opposite end portions of the link with said shafts respectively for rotating the shafts upon movement of the link, one of said means being in closer proximity than the other to the pivot of the link to provide for the rotation of one shaft in advance of the other, and stop means for limiting movement of the first moved shaft to provide for movement of the other shaft upon continued movement of the link. 100 105 110 115

9. A coat hanger forming machine comprising, means for bending and folding a length of wire to form the body portion of a coat hanger with end portions of the wire arranged in parallel relation, twisting mechanism for securing the end portions together, hook forming mechanism for forming a hook on one of the end portions to complete the hanger, ejecting mechanism for ejecting the completed hangers from the machine, and clamping mechanism for gripping the end portions of the wire during the operation of the twisting and ejecting mechanisms, said clamping mechanism including a pair of horizontally aligned jaws, means for normally maintaining the jaws open, means for verti- 120 125 130

5
cally moving the jaws into position to receive therebetween the end portions of the wire, means for closing the jaws to grip the end portions of the wire, and means for opening the jaws and vertically moving the same out of the path of the wire prior to the operation of the ejecting mechanism.

10. In a coat hanger forming machine, a clamping mechanism comprising, a vertically movable, horizontally slidably rod, a jaw member fixedly mounted on the rod, a jaw member slidably mounted on the rod, a vertically slidable bar, means on the rod for normally maintaining the jaws open, a pair of 15 toggle levers pivotally connected with said bar and respectively pivotally connected with said rod and slidably mounted jaw, means for vertically moving said bar and jaws simultaneously, and means for arresting vertical 20 movement of said jaws to provide for the closing thereof upon a continued movement of said bar.

25. A coat hanger forming machine comprising, means for gripping a length of wire, bending mechanism for bending end portions 30 of the wire obliquely to adjacent portions thereof while the wire is held by the gripping means, folding arms operating wholly after the operation of said bending mechanism to bend said adjacent portions in the opposite direction from the bending direction of the end portions to form the body portion of a coat hanger and to bring the end portions into parallel relation, means for 35 curing the end portions together, and means for forming a hook for the hanger.

In testimony whereof, I affix my signature hereto.

CLOISE H. BALDWIN.
